GROVER G. TUTTLE, OF PHILLIPSBURG, NEW JERSEY, ASSIGNOR TO INGERSOLL-RAND COMPANY, OF JERSEY CITY, NEW JERSEY, A CORPORATION OF NEW JERSEY

STEEL RETAINER

Application filed December 21, 1927. Serial No. 241,556.

This invention relates to rock drills, but more particularly to a steel retainer adapted to be attached to fluid actuated rock drills of the hammer type in which the piston reciprocates relatively to the drill steel.

The objects of the invention are to maintain the drill steel in the front head, to render the retainer flexible, to prevent breakage of the retainer and to insure against its accidental oscillation from the retaining position.

Other objects will be in part obvious and in part pointed out hereinafter.

In the drawings illustrating the invention,

Figure 1 is an elevation of the front end of a rock drill having the retainer applied thereto,

Figure 2 is a view similar to Figure 1 showing another view of the retainer,

Figure 3 is an end view of the retainer, and

Figures 4, 5 and 6 are side elevations of modified forms of the invention.

Referring more particularly to the drawings, the invention is shown applied to a rock drill, only the front head A and a portion of the cylinder B of which are shown. These parts, together with others (not shown), comprise the casing of the drill and are held in operative position by spring pressed side bolts C disposed on opposite sides of the drill.

The front head A may be of a well known type which acts as a guide for a drill steel D inserted in the front end of the front head. Only the body portion of the drill steel D is shown. It is, however, to be understood that the drill steel may be of a type provided with a shank adapted to extend into the path of a hammer piston (not shown) reciprocable in the cylinder B.

At the rearward end of the body portion of the drill steel D is formed a collar F which, during the normal operation of the drill, abuts the front end of the front head for limiting the distance which the drill steel may extend into said front head.

On opposite sides of the front head are formed trunnions G of cylindrical shape. The trunnions G are off-set with respect to the longitudinal axis of the front head and may be located in any convenient position relatively to the extremities of the front head.

In accordance with the present invention, means are provided for preventing ejection of the drill steel D from the front head upon the impact of the hammer piston against the drill steel and more particularly whenever there is insufficient resistance to the cutting bit of the drill steel to maintain the drill steel in its rearwardmost limiting position with respect to the drill. These means comprise a steel retainer H which consists of a single piece of wire bent intermediate its ends to form a yoke J. The yoke J is of U-shape and partly encircles the drill steel D forwardly of the collar F at a distance sufficiently removed therefrom to permit limited reciprocation of the collar F together with the drill steel D without impacting against said yoke. The yoke J has integral side arms generally designated by K which extend in a rearwardly direction on opposite sides of the front head A.

The side arms K terminate at their rearward ends in spiral springs L for cushioning the retainer against the effects of the blows of the drill steel on the yoke J. The springs L may consist of any suitable number of coils depending upon the type of front head and the position in which it is desired to mount the retainer thereon. The inner coils O of the springs L are of such form as to snugly receive the trunnions G whereon the retainer H is pivotally supported.

As is well known, retainers of the type to which the present invention pertains are subjected to severe usage and efforts are constantly being made to render them flexible without sacrificing the essential property of strength. In order to incorporate this desirable quality of flexibility in the retainer, the side arms K are provided with coils P at their juncture with the yoke J. The side arms K have rearwardly extending straight portions Q which are engaged by slots R in the sides of the front head A for the purpose of preventing unintentional displacement of the retainer H. The rearward ends of the straight portions Q of the side arms are developed into coils S located intermediate the coil springs L and the straight portions Q. The coils S are reversely wound with respect to

the coil springs L and the coils S and springs L of each side arm are preferably aligned parallel to the axis of the drill steel D.

During the operation of the drill, the retainer H will occupy a position in which the straight portions Q of the side arms K are in engagement with the grooves R in the front head. The retainer is thus held against accidental oscillation from the retaining position in which the yoke J lies in the path of the collar F. With the retainer in this position, the rock drill and the drill steel D may be removed from the vicinity of the drill hole as a unit since the yoke J will engage the collar F and enable the rock drill to be used as an implement for pulling the drill steel D out of the drill hole.

Whenever it is desired to remove the drill steel D and substitute another therefor, the retainer H may be oscillated about the trunnions G a sufficient distance to remove the yoke J out of the path of the collar F. After another steel has been inserted into the front head, the retainer may again be rocked to its retaining position wherein it will be held by the grooves R.

In the modification illustrated in Figure 4, the retainer T, like that shown in the preferred modifications, consists of a single piece of wire bent intermediate its ends to form a yoke U to serve as an abutment for the collar of the drill steel.

The retainer has upwardly extending side arms V which are connected to the yoke U by curved portions W. At the rearward ends of the side arms V are formed the spiral springs L for absorbing the blows of the drill steel against the yoke U. Straight portions X extend rearwardly from the curved portions W and develop into coils S adjacent the springs L and reversely wound with respect thereto to cooperate with the springs L for cushioning the yoke against the effects of the blows of the drill steel and to eliminate angular stresses in the side arms.

The modification shown in Figure 5 is adapted more particularly for use on rock drills on which the pivotal points or trunnions G are so located as to preclude the use of cushioning means at this extremity of the retainer. The side arms of the retainer are provided at their rearward extremities with loops or coils Y for pivotally engaging the trunnions. The loops Y may be extended to form coils Z intermediate the ends of the retainer and said coils Z are developed into straight portions b which may be engaged by the grooves R of the front head for holding the retainer in retaining position. The yoke U is connected to the front ends of the straight portions b of the retainer by coils c which cooperate with the coils Z reversely wound with respect to the loops Y for the purpose of rendering the retainer flexible.

The modification illustrated in Figure 6

comprises a yoke U connected to the side arms d by means of coils e. The straight portions f of the side arms d are so located with respect to the yoke U as to enable them to lie in the grooves R of the front head when the retainer is in its retaining position. At the rearward ends of the side arms d are formed the spiral springs L which cooperate with the coils e for absorbing the blows of the drill steel against the yoke U.

The operation of the modified forms of retainers shown in Figures 4, 5 and 6 is substantially like that previously described in connection with the retainer shown in Figures 1 to 3 inclusive. As may be readily observed, the retainers shown in the modifications differ with respect to each other in the matter of flexibility. These structural differences render them particularly applicable for various types of drills and for certain usages. These retainers, however, as that in the preferred modification are sufficiently yieldable to enable them to fully withstand the severe blows to which they are subjected.

A few of the desirable features of the invention are that those portions, as for instance the straight portions of the side arms, which are in engagement with the front head for locking the retainer in retaining position lie in planes parallel with the plane of movement of the retainer upon the impact of the drill steel thereagainst. Lateral displacement of the straight portions during the movement of the retainer is prevented by the secondary coils placed between the straight portions and the coils at the ends of side arms. As a result of this construction the retainers are not subjected to the severe angular stresses which are largely responsible for the excessive breakage of retainers of this type.

Another advantageous feature of the present invention is the protection afforded the retainer by forming the coils adjacent the yoke. This construction has been found to further eliminate the chances of breakage since a positive spring effect is provided for the retainer at that point at which the retainer is called upon to withstand the most severe strains.

I claim:

1. In a steel retaining device for rock drills, the combination with a front head having trunnions, a drill steel guided by the front head, a collar on the drill steel, and a retainer comprising a yoke to act as an abutment for the collar and side arms on the yoke terminating in coils for engaging the trunnions, of secondary coils adjacent the first said coils and being reversely wound with respect thereto, and straight portions on the side arms forwardly of the return bent portions of said secondary coils and adapted to engage the front head to prevent accidental oscillation of the yoke from the retaining position.
2. In a steel retaining device for rock drills,

the combination with a front head having cylindrical trunnions, a drill steel guided by the front head, a collar on the drill steel, and a retainer comprising a yoke to act as an abutment for the collar and side arms having
5 integral spiral springs at their rearward ends, the innermost coils of said springs being adapted to pivotally engage the trunnions, of secondary coils adjacent said springs and being reversely wound with respect thereto,
10 said springs and said secondary coils on each side arm being aligned parallel to the axis of the drill steel, and straight portions on the side arms forwardly of the return bent portions of said secondary coils and adapted to engage the front head to prevent accidental oscillation of the yoke from the retaining position.
15

In testimony whereof I have signed this
specification.

20 GROVER G. TUTTLE.
